UNITED STATES PATENT OFFICE.

ERNST BENNO BERTHOLD KUCKUCK, OF CHARLOTTENBURG, GERMANY

TIE-PRESERVING CYLINDER-CAR.

No. 808,761.

Specification of Letters Patent.

Patented Jan. 2, 1906.

Application filed August 31, 1905. Serial No. 276,667.

To all whom it may concern:

Be it known that I, ERNST BENNO BERTHOLD KUCKUCK, a subject of the German Emperor, residing at Charlottenburg, Germany, have invented certain new and useful Improvements in Tie-Preserving Cylinder-Cars, of which the following is a specification.

My invention relates to that class of tie-preserving cylinder-cars adapted to be used in connection with a cylinder or tank for introducing ties to be treated into the cylinder, supporting them therein during treatment, and removing them therefrom.

It relates particularly to the means for enabling the largest possible number or bulk of ties to be handled in a tank or cylinder of a given size.

The principal object of my invention is to provide a simple, economical, and efficient tie-preserving cylinder-car.

A further object of the invention is to provide a cylinder-car and tie-preserving cylinder adapted to enable the largest possible number or bulk of ties to be introduced into a cylinder or tank of given size, supported therein during treatment, and removed therefrom.

Other and further objects of the invention will appear from an examination of the drawings and the following description and claims.

The invention consists in the features, combinations, and details of construction hereinafter described and claimed.

In the accompanying drawings, Figure 1 is a transverse sectional elevation of a tie-preserving cylinder-car and cylinder constructed in accordance with my improvements; Fig. 2, a plan view of the car, and Fig. 3 a side elevation of the car.

In the art to which this invention relates an air-tight tank is employed capable of sustaining the desired pressure and containing fluid under pressure adapted to be forced into the ties to be treated for the purpose of rendering them less susceptible to the detrimental effects of atmospheric conditions to which they are exposed in use. For this purpose it is very desirable that the tank or cylinder in which the ties are to be treated shall be as nearly as possible of no greater dimensions than is essential to enable it to hold the desired number or bulk of ties. In other words, it is important that the car or carriage shall be of such construction and dimensions as to support the largest possible num-

ber of ties in the limited space afforded by the cylinder without diminishing the size of the car-wheels to a detrimental extent.

In constructing a tie-preserving cylinder-car and cylinder in accordance with my improvements I provide a cylinder *a* in the form of a shell of metal of the necessary strength to withstand the pressure to which it is subjected in operation and having an opening at one end thereof provided with door mechanism which may be of any ordinary and well-known type adapted to form a tight cylinder when the door is closed. This cylinder is provided with track-rails *b*, extending longitudinally thereof, which are secured to its inner surface by means of brackets *c*, rivets *d* connecting the brackets, and thereby the rails, to the cylinder, and bolts or screws *e* connecting the rails to the brackets.

My improved cylinder-car is formed entirely of metal and consists of a frame having longitudinal members formed of angle-irons *f*, arranged in two pairs on opposite sides of the car, the two upright flanges of each of such pairs of angles being connected by a channel-iron *g*, having depending side flanges, by means of rivets *h*, to the angle-irons, forming therewith hollow side sills and also forming housings for receiving supporting car-wheels *i*. The channel-irons extend from end to end of the car-frame and cover the car-wheels mounted in such housings. Each pair of angle-irons, with the channel-iron secured thereto, thus forms a longitudinal sill *g* of the necessary strength to withstand the strains to which the car-frame is subjected in use, and they also house the wheels and support and form bearings for the journals or axles, as hereinafter described. The transverse members of the car-frame consist of a pair of bent or curved channel-irons *j*, arranged at opposite ends of the car-frame and secured to the longitudinal members by means of gusset-plates *k* and rivets *l*, so as to connect such longitudinal side sills and therewith form the car-frame. The opposite ends of each of these transversely-extending channel members are curved upwardly from the points at which they are secured to the longitudinal members of the frame, so that each of such transverse channel-beams forms a pair of curved side arms *m*, which extend upward and outward at the necessary angle to conform substantially to the curvature of the cylinder in connection with which the car is used. These transverse channel mem-

bers are preferably so disposed that their flanges extend outwardly and downwardly, their web portions being upon the top sides thereof, and thus adapted to be firmly secured to the longitudinal members of the frame, which extend over and rest upon the upper sides of such transverse members, as shown in Figs. 1 and 2. Braces *n* extend obliquely across the bottom portion of the frame and are secured to the longitudinal members by means of rivets, so as to firmly brace the central portion of the frame, and the gusset-plates *k* are in curved form, so as to conform to the curvature of the transverse channel members and provide a connection between them and the longitudinal members of great rigidity and strength and adapted to occupy as little otherwise available space as possible. Each pair of supporting-wheels is mounted upon an axle *o*, which extends transversely of the car, each of such axles being journaled in bearings formed by metallic straps or journal-boxes *p*, secured to the lower surface or transverse flanges of the longitudinal angle-irons or frame members by means of bolts *q* and nuts *r*. By this means it will be readily seen that the car-wheels are housed between the longitudinal members of the frame and that the journals or axles being mounted in the bearings secured to the longitudinal members of the frame a framework of great efficiency and strength is provided resting upon wheels which are inclosed largely within the main framework of the car, so that the wheels and frame occupy as little space as is consistent with efficiency in operation. The outer ends of the transverse frame members are connected by means of upwardly curved or arched bows *s*, the opposite ends of each of said bows being detachably secured to the transverse or upwardly-extending side frame members by means of hook portions *n*, inserted into perforations in the transverse channel-irons, and collar-pins 45 extending through perforations in the hook portions.

A guide *v* is mounted on the outside of each of the track-rails, and a guard *u* is secured to the car-frame, having a depending hook portion extending inside of and beneath each of the guide rails or plates, so as to slidably engage the under side thereof and hold the car upon the rails.

I claim—

- 55 1. In a car of the class described, the combination of a car-frame consisting of a pair of hollow longitudinally - extending side sills, transverse frame members extending across the opposite ends of such hollow longitudinal side sills connecting them and forming therewith a car-frame, and car-supporting wheels extending into the hollow portion of the side sills for supporting such sills and thereby the car.

- 65 2. In a car of the class described, the com-

bination of a car-frame consisting of a pair of longitudinally-extending sills each formed of a pair of angle-irons having upwardly-extending flange portions forming a space therebetween, a top member extending over such space and secured to the upper edges of such flanges, transverse frame members connecting such longitudinal sills, and car-supporting wheels extending into the hollow portions of such longitudinal sills for supporting the car-frame.

3. In a car of the class described, a car-frame having longitudinal sill members provided with spaces therebetween for receiving car-supporting wheels, car-supporting wheels journaled upon and extending between such longitudinal sill members of the car-frame and housed thereby, and channel-beams extending transversely across the car connecting such longitudinal sill members and having upwardly-curved portions at their opposite ends forming side supports for the contents of the car.

4. In a car of the class described, a car-frame having longitudinal side sill members provided with spaces therebetween and having channel - beams secured along the upper edges thereof forming hollow side sills, car - supporting wheels extending into the hollow portion of such side sills, and axles upon which such car-supporting wheels are mounted.

5. In a car of the class described, a car-frame having angle-irons arranged in pairs on opposite sides thereof forming longitudinal sill members and forming spaces between the upwardly-extending flange portions of such angle-irons, channel-irons mounted between and secured to the upwardly-extending flange portions of such angle-irons and forming therewith hollow longitudinal sills having openings at the bottoms thereof, and car-supporting wheels mounted beneath and extending into the hollow portions of such sills.

6. In a car of the class described, the combination of a car-frame consisting of a plurality of hollow longitudinal side sills open at the under side thereof, channel-beams extending transversely of the car secured to and connecting such side sills and each provided with integral upwardly-extending end portions forming side supports for the contents of the car, and supporting car-wheels rotatably mounted and extending into the hollow portions of such hollow side sills.

7. In a car of the class described, the combination of a car-frame consisting of hollow longitudinal side sills, transverse frame members connecting such side sills and provided with integral upwardly-extending end portions forming side supports for the contents of the car, axles rotatably mounted upon the longitudinal side sills, and car-supporting wheels mounted upon such axles and ex-

tending into the hollow portions of the side sills and housed thereby.

ture of the inner surface of the cylinder, and supporting car-wheels mounted upon the track-rails of the cylinder and extending into the hollow portions of such hollow side sills. 15

8. In an apparatus of the class described, the combination of a metallic cylinder, track-
5 rails extending longitudinally along the inner surface thereof, a car having a plurality of hollow longitudinal side sills open at the under side thereof, channel-beams extending transversely of the car secured to and connecting such side sills and each provided with integral upwardly-extending end portions curved to correspond with the curva-

10 to 15 In witness whereof I have hereunto signed my name, this 21st day of July, 1905, in the presence of two subscribing witnesses.
